UNITED STATES PATENT OFFICE.

JOHN H. STEWART, OF RUTHERFORD, NEW JERSEY.

DOOR HANGING AND SECURING MEANS.

Application filed March 25, 1921. Serial No. 455,391.

To all whom it may concern:

Be it known that I, JOHN H. STEWART, a citizen of Canada, and a resident of Rutherford, in the county of Bergen and State of New Jersey, have invented a new and Improved Door Hanging and Securing Means, of which the following is a description.

My invention relates to sliding doors for freight cars, and more particularly the invention relates to a freight car door adapted to have lateral movement to or from the doorway in addition to its sliding movement, whereby to effect a tight fitting of the door in the doorway.

The invention has for its general object to provide suspension means for the door, whereby the door may with facility be readily opened and may be quickly and tightly closed, as well as to provide means coordinated with the suspension means for fastening the door in the closed position.

Reference is to be had to the accompanying drawings forming a part of this specification, it being understood that the drawings are merely illustrative of one example of the invention.

Figure 1 is an elevation of a portion of a freight car and the door thereof embodying my invention;

Figure 2 is a fragmentary longitudinal vertical section of a freight car giving an inside view of the door and its appurtenances;

Figure 3 is a horizontal section on the indicated line 3—3, Figure 1;

Figure 4 is a view in the plane indicated by the dot-and-dash line 4—4, Figure 1, but showing the door in the open position as in Figure 2;

Figure 5 shows the upper portion of the door in side elevation by dotted lines and the car roof in vertical section by full lines;

Figure 6 is a transverse vertical section on the line 6—6, Figure 3;

Figure 7 is a transverse vertical section on the line 7—7, Figure 4;

Figure 8 is an enlarged detail in horizontal section given to show the lower stop bracket and bearing, as hereinafter referred to;

Figure 9 is an enlarged detail on the line 9—9, Figure 2.

In the illustrated example of my invention the letter A indicates the door; B, the door frame; and C, portions of the car body. The

numeral 10 indicates a suspension bar of 55 suitable flat material which is pivoted at its upper end to the door A at the approximate vertical median line thereof at the inner side of said door as at 11. The lower end of the suspension bar 10 is pivotally connected as at 12 to a suspension bar 13 preferably between the ends of said bar for a reason that will appear. Above the pivot 12 the suspension bar 13 is pivotally secured as by a pin 14 to bracket 15 at one side of the doorway on 60 the face of the adjacent vertical member or jamb. Thus, the bars 10, 13 may have movement on the pivots 11, 12 and 14 with the sliding of the door A. The bracket 15 is adapted to swing in a plane transverse to the 65 plane of the doorway by reason of being pivotally secured at its lower end as at 16, the pivot pin 14 being at the upper end of said bracket. Advantageously, also, the swingable bracket 15 has a slot and pin connection with the door frame, there being a transverse slot 17 in said bracket, and a pin 18 passing through said slot into the door frame and limiting the swinging movement 70 of the bracket. 75

The bar 10 in coaction with the bar 13 or with that portion of the bar between the pivots 12 and 14, constitutes a suspension means for the door but I provide the bar 13 to extend below the pivot 12 a substantial 80 distance to assist as one means to prevent the turning of the door in its own plane with the pivot 11 as a center, the lower end of the bar 13 having a transverse pin 19 having movement in a vertical slot 20 in a guide bracket 21 suitably secured to the inner face 85 of the door A as by rivets 22, the broad head 19^a of the pin 19 being housed within said bracket 21 for preventing displacement of the pin. Guide means for the door is provided also in the form of brackets 23, 24 applied to the door at the outside and extending above the same, together with a longitudinal track-like guide rail 25 secured to the car C above the door, said guide rail 25 being of a length to effect engagement 90 with the brackets 23, 24 for the complete sliding movement of the door to or from the closed position. The weight of the door is sustained by the bars 10, 13 not by brackets 23, 24 and the guide rail 25. The rail 25 is 95 U-shaped in cross section, being upturned at the inner side as clearly shown in Figures 100 105

6 and 7 and the upper ends of the brackets 23, 24 are turned outwardly and downwardly giving them a hook form at the upper ends, the reverse of said U-shaped rail 25. The bracket 23 engages the rail 25 at all times both in the closed and open positions of the door but the bracket 24 is adapted when the door is at the doorway B to move toward or from the doorway and 10 into and out of engagement with the guide rail 25. For the movement of the bracket 24 into and out of engagement with the guide rail 25, the latter is formed in its upturned portion with a cut-out 26 affording 15 clearance for the hooked end of bracket 24 to move laterally relatively to said guide rail with the movement of the door transversely to the plane of the doorway. A stop bracket 27 is provided on the body C at 20 the bottom adjacent to that side of the door frame having the swinging bracket 15.

The door A, it will be observed, when in the closed position, lies in a plane outside of the pivotal connection 14 between the suspension element 13 and the car body and thereby the door has a tendency to move outwardly from the opening under its own weight. I provide means for effecting the tight closure of the door A, and for fastening the door in the closed position of Figure 3, said means consisting of a vertical rod 30 adapted to turn at its upper and lower ends respectively in bearings 28, 29 on the car body to permit said rod to turn 35 through 180°. On the rod 30 are lateral fastener arms 31, 32 near the top and bottom of the rod respectively, the lower arm 32 being longer and constituting a hasp to permit the arm to pass over a staple 33 on the 40 door A adapted to receive a padlock. The arrangement of the lock rod with its arms is such that if the door A in the closing movement thereof arrives adjacent to the doorway, but not quite in register therewith, 45 the arm 32 is grasped to turn the rod 30 on its axis and cause said arm 32 to be pressed against the door at the adjacent edge whereby the door will be forced to move both in its own plane and laterally inward to the 50 plane of the doorway. The rod 30 is half-round and when in position with the arms 31, 32, away from the door, said rod is accommodated in a concave vertical recess c in the car siding adjacent to the door frame B 55 and as indicated in Figures 3 and 4.

At the opposite side of the doorway from the locking rod 30 keeper plates 34 are secured to the car to project beyond the door frame, whereby the adjacent edge of the 60 door may be slid beneath said keepers when the door is moved to position at the doorway under pressure of the arm 32.

A keeper 35 is provided on the side of the car body to engage that edge of the door 65 farthest from the door opening when the

door is at the limit of its open position, for holding the door at said edge against swaying outwardly from the car body. The door is guided to the keeper 35 by the rail 25 and the bracket 24.

It will be observed that the distance from the pivot 11 to the pivotal connection 12 is the same as the distance from the pivot 14 to the pivotal connection 12 and, since the door is held at the top against upward movement in its own plane, or movement about the pivot 14, by the track 25 and its supporting means, and since at the bottom there is a slot and pin connection between the door and the element 13 by reason of the pivot 19 sliding in the guide slot 20, which is directly in alignment with the pivot point 11, the door is constrained to move in a straight line without rising or falling movement.

It will be observed also that by the suspension means described I am enabled to dispose the suspension means at the inside of the door, notwithstanding the limitations as to space determined by the unalterable 90 positions of the frame beams of the car body above and below the door opening, the result being attained by reason of the suspension elements being arranged to impart direct rectilineal movement to the door and by the fact that the pivotal connection at 95 14 is at the door opening below that car beam which is positioned above the door. Therefore, the suspension means is accommodated between the upper and lower longitudinal frame beams and therefore may be mounted close to the door in a plane parallel with the door.

I would state in conclusion that while the illustrated examples constitute practical embodiments of my invention, I do not limit myself strictly to the mechanical details herein illustrated, since manifestly the same can be considerably varied without departure from the spirit of the invention as 110 defined in the appended claims.

Having thus described my invention, I claim:

1. In combination with a freight car and a sliding door thereon, a suspension element pivotally secured to the door, at the approximate vertical median line of the latter near the top, a coacting element pivotally secured to the car body and to the first element below the pivotal connection between said first element and the door, so that both elements may have movement in either direction in their own planes and approximately parallel with the sliding path of the door, and means on the car body, at the doorway, to which said second element is pivotally secured, said means being mounted to have movement transversely to the doorway to permit the door to move transversely into and out of the doorway.

2. In combination with a freight car and a sliding door thereon, of a suspension element pivotally secured to the door near the top approximately at the vertical median line of the door by a single pivotal connection, and an element pivotally secured between its ends to said suspension element, said second element being pivoted at its upper end to the car body at the doorway and pivotally and slidably engaged at its lower end with the door at approximately the vertical median line of the door. 5
3. In combination with a freight car and a sliding door thereon, a guide rail on the car body above the door, downturned brackets on said door at the top adapted to have engagement with said rail in the sliding movements of the door, and suspension means connected with the body and suspended on the door at a single point and sustaining the weight of the door, said brackets and guide rail being relieved of the weight of the door. 10
4. In combination with a freight car and a sliding door thereon, a guide rail on the car body above the door, brackets on said door near each side edge to have engagement with said rail in the sliding movements of the door, and suspension elements pivotally connected with each other and having pivotal connection with the door and car body respectively, said suspension elements sustaining the weight of the door and relieving the brackets of said weight. 15
5. In combination with a freight car and a sliding door thereon, means secured to the car body near the top of the doorway and to the door at the approximate vertical median line of the door near the top and sustaining the weight of said door, the lower end of said means having connection with the door and said means being responsive to sliding movements of the door. 20
6. In combination with a structure, and a sliding door thereon, movable transversely into or away from the doorway in addition to the sliding movements, and suspension means pivotally secured to said door and to said structure to swing in a plane approximately parallel with the plane of the door and to swing transversely to the plane of the door to be thus constrained to conform to the sliding and transverse movements of the door. 25
7. In combination with a freight car and a sliding door thereon, a suspension element pivotally secured to the door, a second suspension element pivotally connected between its ends with said first element below the point of connection between said first element and the door, means pivotally connecting the upper end of the second element with the car body adjacent the door opening, said door being slidable past said pivotal connection with the car body from the closed to the open position, and means affording guided sliding engagement between the lower end of said second element and the door. 30
8. Suspension means for a sliding freight car door comprising pivotally connected suspension elements, one of said elements being adapted to be secured to the car door to suspend the latter, and a third element to which said second element is pivotally secured, said third element having means whereby to pivotally mount it at the doorway to have movement transversely to the plane of said doorway. 35
9. Suspension means for a sliding freight car door comprising pivotally connected suspension elements, one of said elements being adapted to be secured to the car door to suspend the latter, and a third element to which said second element is pivotally secured, said third element having means whereby to pivotally mount it at the doorway to have movement transversely to the plane of said doorway; together with means to limit the transverse movement of said third element. 40
10. The combination with a freight car and a sliding door thereon, of a suspension arm pivotally secured to the door approximately at the vertical median line of the door, a second element pivotally secured to the first element below the point of connection between said first element and the door, and means pivotally mounting the second element at its upper end on the car body at the doorway, said elements being movable in their own planes in either direction past the securing point of the second element, the second element being furthermore mounted to have transverse movement relatively to the plane of the doorway to permit the door and suspension means to move toward or from the plane of the doorway in addition to the sliding movements of the door and the movements of said suspension elements in their own plane. 45
11. The combination with a freight car and a sliding door thereon, of pivotally connected suspension elements, one of which is pivotally secured at its upper end to the door, means securing the opposite end of said connected suspension elements to the car body at one side of the doorway to have swinging movement in their own planes approximately parallel with the plane of the doorway, and movable transversely toward or from the doorway. 50
12. The combination with a freight car and a sliding door thereon, of suspension means connected respectively with the door and with the car body at the doorway, and pivotally connected with each other, the said connection with the car body permitting transverse movement of the door toward or from the plane of the doorway, and means to lock the door in closed position, the said door when closed lying in a plane in front of the doorway. 55

of the point of connection between the suspension means and the car body to give it a tendency to sway outwardly when released by the locking means.

5 13. The combination of a freight car and a sliding door thereon, said door being adapted to have transverse movement toward or from the doorway in addition to its sliding movements, and suspension means 10 secured to the door and to the car body at the door opening and responsive to the sliding and transverse movements of the door, said door when in the closed position lying in a plane outward of the connection between 15 the suspension means and the car body, whereby to tend at one side edge portion to move outwardly under its own weight when in closed position and door-retaining means to hold the door against said outward movement.

20 14. The combination of a freight car and a sliding door thereon, said door being adapted to have transverse movement toward or from the doorway in addition to its 25 sliding movements, and suspension means secured to the door and to the car body at the door opening and responsive to the sliding and transverse movements of the door, said door when in the closed position 30 lying in a plane outward of the connection between the suspension means and the car body, whereby to tend at one side edge portion to move outwardly under its own weight when in closed position door-re- 35 taining means on the car to engage the door at one edge in the open position of the door, and door-retaining means on the car to engage the door at the opposite edge in the closed position of the door.

40 15. The combination with a structure having a sliding door, of suspension means for said door comprising elements pivotally connected with each other to move in their own planes substantially parallel with the 45 plane of the door, one end of said means being pivotally secured to said structure at the doorway and the other end having a one-point pivotal suspending connection with the door on a line drawn approxi- 50 mately through the medial plane of the door, as well as having a pivotal and vertically slidable connection with the door near the bottom, the two points of connection with the door being in vertical alinement.

55 16. The combination with a structure having a sliding door, of suspension means for said door comprising elements pivotally connected with each other to move in their own planes substantially parallel with the 60 plane of the door, one end of said means being pivotally secured to said structure adjacent to the top of the door opening, and the other end of said means having a one-point pivotal suspending connection with 65 door near the top of the latter on a line

drawn approximately through the medial vertical plane of the door; together with means affording a guided slidable and pivotal engagement between the door and said suspension means below the point of the 70 door suspension.

17. The combination with a structure having a sliding door, of suspension means for said door comprising elements pivotally connected with each other, to move in their own planes relatively to each other, means mounted for pivotal movement transversely of the plane of the doorway and pivotally securing one end of said suspension means to said structure near the top of the doorway, the other end of said suspension means having a one-point pivotal suspending connection with the door on a line drawn approximately through the medial vertical plane of the door.

85 18. In combination with a freight car and a sliding door thereon, of suspension means disposed at the inner side of the door and comprising a suspension element pivotally secured to the door and a coacting element pivotally secured to the car body at the interior, and to the first element below the point of connection between the door and said first element, the pivotal connection with the car body and the pivotal connection with the door being equidistant from the pivotal connection between said elements, together with means pivotally and slidably securing said coacting element to the door near the bottom.

90 19. In combination with a freight car, and a sliding door thereon, of suspension means for the door disposed at the inner side of the latter and comprising a suspension element pivotally secured to the door near the top thereof, and a coacting element mounted on the car body at the door opening at a point below the top of said opening to swing in a plane parallel with the plane of the door as well as transversely to the door, said coacting element being pivotally secured to the first element below the point of connection between the door and said first element.

100 20. In combination with a freight car and a sliding door thereon, of means to suspend the door and cause the door to have a sliding movement in a rectilinear path, said means comprising a suspension element pivotally secured to the door near the top, and a coacting element pivotally secured to the car body and to the first element below the point of connection between the door and said first element, said elements being of the same length from their pivot points to the point of connection between said elements, together with means pivotally and slidably securing said coacting element to the door near the bottom.

105 21. In combination with a freight car and

a sliding door thereon, of suspension means disposed at the inner side of the door and comprising a suspension element pivotally secured to the door and a coacting element pivotally secured to the car body at the interior, adjacent the door opening, and to the first element below the point of connection between the door and said first element, said

second mentioned element having guided engagement with the door below the point of connection with the first element, said door having a path of movement to carry its point of connection with the suspension element past the point of connection with the car body.

JOHN H. STEWART.
